M. M. KANDLE,
DEVICE FOR DETECTING INACCURATELY FED SHEETS OF PAPER,
APPLICATION FILED DEC. 31, 1908.

923,658.

Patented June 1, 1909.

UNITED STATES PATENT OFFICE.

MATTHIAS M. KANDLE, OF LONGMEADOW, MASSACHUSETTS, ASSIGNOR TO SPRINGFIELD PRINTING & BINDING COMPANY, OF SPRINGFIELD, MASSACHUSETTS, A CORPORATION.

DEVICE FOR DETECTING INACCURATELY-FED SHEETS OF PAPER.

No. 923,658.

Specification of Letters Patent.

Patented June 1, 1909.

Application filed December 31, 1908. Serial No. 470,226.

To all whom it may concern:

Be it known that I, MATTHIAS M. KANDLE, a citizen of the United States of America, residing at Longmeadow, in the county of 5 Hampden and State of Massachusetts, have invented new and useful Improvements in Devices for Detecting Inaccurately-Fed Sheets of Paper, of which the following is a specification.

10 My present invention relates to improvements in reset mechanisms for printing presses and is especially adapted for multi-color printing, and more particularly it is an improvement on the construction shown, 15 described, and claimed in my prior United States Letters Patent for improvement in "Devices for detecting inaccurately fed sheets of paper" dated December 29, 1908 and numbered 908,412.

20 The invention in said prior patent relates wholly to the detection and rejection of an inaccurately fed sheet of paper, but does not contain any automatic means for resetting the mechanism after a sheet has been detected and rejected. In said patent, in order 25 to reset the mechanism after the sheet has been detected and rejected, it is necessary to use manual or foot means for effecting this resetting of the press, and such means for resetting the mechanism causes an unnecessary amount of time and labor for the operative 30 who has charge of the printing operation. It is therefore with this end in view that my present invention has been devised for increasing the efficiency of the printing press.

35 Broadly, the present invention consists in associating with the electro magnet lock of my aforesaid prior patent, means for effecting the reset of the paper-detecting and rejecting mechanism after the operation of said mechanism by an inaccurately fed or placed sheet of paper in the press.

In the drawings forming part of this application,—Figure 1 is a diagrammatic view 45 of my improvements showing such parts of the press as is necessary to clearly illustrate my invention, and particularly the means for causing the mechanisms to operate when an inaccurately fed sheet of paper is placed in the machine. Fig. 2 is a detail perspective 50 view of the locking means between the electro magnetic latch mechanism and the lever which is actuated by the main cam-shaft for

effecting the resetting of the detecting mechanism.

Referring to these drawings in detail,—
a designates the usual printing roller proper; b the foot-board, and c the feed-table of the press. The main cam-shaft is designated by d. The stops or guides which are located at 60 right angles to each other, are shewn at e. The details of the construction of these guides are clearly shown in my aforesaid prior patent and also the electro-magnetic lock, at f.

The battery and the manually operated switch is shown at g and h, and the wiring connection between the stops e and the lock f at h¹ and i.

Electrically connected to the wire i is a 70 contact-piece j with which engages a brush k. This contact-piece is carried on the surface of an insulated ring m which is secured to the press cam-shaft d and it will therefore be apparent that when the brush k engages the contact-piece j the electric circuit will be completed through the stops e, battery h, switch g, and electro magnetic lock f.

The lock f is not operated unless the sheet of paper is inaccurately fed; that is, the contact points at one of the stops e will be closed causing a current to flow to the lock f and actuate the same, as fully described in my prior patent.

Secured to the press cam-shaft d is a cam 85 n with which engages the anti-friction roller o of the lever p that is pivoted at q on the upper end of a standard r.

A tension spring s normally holds the lever p and roller o in engagement with the cam n whereby this lever is constantly vibrated about its pivotal point q causing its outer end t to alternately rise and fall. This end of the lever has attached thereto a hook u by means of a pivot connection v. This hook is guided in its rising and falling movements by means of a bent arm or hook w that is secured to the upright rod x which is pivotally connected to the latch-bar y of the electro magnetic lock f.

The rod x is pivotally connected to the latch-bar y of the electro-magnetic lock f at the point z and extends upward through the foot-board b of the press, as shown at 2. Secured to the rod x are two collars 3 and 4 that are provided with radially projecting

pins 5 and 6. The pin 6 serves in connection with the hook *w* to normally prevent the upper end of the hook *u* from engaging the pin 5 during the rising and falling of the outer end *t* of the lever *p*.

The link connection, designated by the reference characters 7, 8, 9, 10 and 11, that extends between the latch-lever *y* and the rejecting fingers 12 is the same as that shown 10 and described in my aforesaid prior patent No. 908,412. The latch lever *y* is pivoted to the frame 13 at the point 14. 15 designates a tension spring that extends between the bottom of the foot-board *b* and the outer end 15 of the latch-lever *y*. The stops *e* are raised and lowered by the cam 16 and arm 17 in the same manner as described in my said patent in order to allow the sheets of paper to be fed to the printing roller in the usual 20 manner.

Referring now to the operation of my improvement: It is understood that the sheet of paper which is shown in dotted lines at 18 is inaccurately fed, that is to say it does 25 not break the electric circuit at all of the steps or guides *e*, and the circuit is therefore closed to the electro-magnetic lock *f*, permitting a current to flow to the electro magnets shown in dotted lines at 19 of the lock. 30 The contact-piece *j* and the brush *k* are supposed to be in contact at this time, that is to say the brush *k* engages the piece *j* a slight interval of time before the stops or guides *e* are operated. This current re- 35 leases the latch-lever *y* from its locked position and by the aid of the spring 15 the latch-lever is violently thrown to the dotted line position 20 causing the upper end of the hook *u* to be moved into the path of the pin 5 on the rod *x*: Then, when the rod *x* is 40 operated by the cam *n* from the shaft *d*, the lever *y* will be automatically reset by the press-cam.

The operation of the rejecting fingers 12 45 will be actuated by the spring 15. It will therefore be seen that the elements *n*, *o*, *p*, and hook *u* acting on the latch-lever *y*, serve to automatically reset the electro magnetic block *f* ready for another operation.

What I claim, is:—

1. A reset mechanism for printing presses having in combination with the press cam-shaft, a lever operable therefrom, a latch-lever, a rejecting finger, connecting means between the latch-lever and said finger, and means for causing the latch-lever to be reset, or moved to its usual position by said lever, when the latch-lever is released, and electro-magnetically operated means for releasing the latch-lever. 55

2. A reset mechanism for printing presses having in combination with the guides means for detecting inaccurately fed sheets of paper, and an electro-magnetically released latch-lever electrically connected to said guides when the paper is so fed, rejecting fingers, a press-cam shaft, a lever operable therefrom, means carried by the latch-lever for causing said lever to reset the latch-lever and said fingers after the latch has been released, as described. 60

3. A mechanism of the class described comprising a lever, a cam for operating the same, an electro-magnetically released latch-lever, a rejecting finger connected to the latch-lever, means for resetting the latch-lever from the said first mentioned lever after the latch-lever has been released, said means including a hook element carried by the lever. 75

4. A mechanism of the class described comprising a lever, a cam for operating the same, an electro-magnetically released latch-lever, a rejecting finger connected to the latch-lever; means for resetting the latch-lever 85 from the said lever after the latch-lever has been released, said means including a rod pivoted to the latch member and provided with a projection, and said lever having a hook element for engaging the projection of the latch member, and means for normally retaining the hook element out of engagement with the projection. 90
